UNITED STATES PATENT OFFICE.

JAMES C. HIGHTOWER, OF ATLANTA, GEORGIA, ASSIGNOR OF ONE-HALF TO PAUL F. BAUKNIGHT, OF ATLANTA, GEORGIA.

BROOM.

1,112,614.

Specification of Letters Patent.

Patented Oct. 6, 1914.

Application filed November 3, 1913. Serial No. 798,987.

To all whom it may concern:

Be it known that I, JAMES C. HIGHTOWER, a citizen of the United States, residing at Atlanta, in the county of Fulton and State 5 of Georgia, have invented certain new and useful Improvements in Brooms, of which the following is a specification.

My invention relates to brooms and has particular reference to improvements in a 10 broom embodying novel means to detachably connect the handle with the body or brush portion thereof, whereby after the body or brush portion has become worn, or otherwise injured, the same may be removed from the 15 handle and a new one substituted therefor.

An important object of the invention is to provide simple and inexpensive means to properly detachably connect the handle and body or brush portion of a broom, 20 whereby they will remain securely connected and may be separated when desired.

A further object of my invention is to provide means of the above mentioned character, which will not increase the cost of 25 manufacturing the brooms, but will tend to reduce the same.

A further object of the invention is to provide novel means for securely attaching the broom corn or straw, constituting the 30 brush portion of the broom, to a tubular casing which detachably receives the handle of a broom, positively preventing the broom corn or straw from shedding.

Other objects and advantages of this in- 35 vention will be apparent during the course of the following description.

In the accompanying drawings forming a part of this specification and in which like numerals are employed to designate like 40 parts throughout the same, Figure 1 is a side elevation of the broom, parts thereof being broken away, Fig. 2 is an end elevation of the same, Fig. 3 is a central longitudinal sec- 45 tional view through the same, Fig. 4 is a horizontal section taken on line 4—4 of Fig. 1, Fig. 5 is a side elevation of the lower portion of the handle receiving tube showing an attaching tongue, Fig. 6 is a perspective view of a supplemental securing plate, and, 50 Fig. 7 is a similar view of a tying element.

In the drawings, wherein for the purpose of illustration is shown a preferred embodiment of my invention, the numeral 10 designates a tubular handle receiving sleeve or 55 socket, which is preferably formed of sheet

metal owing to the strength and lightness of such material. At the extreme inner end of the handle receiving sleeve 10, its material is bent inwardly, forming stops or shoulders 11, to positively limit the downward move- 60 ment of a handle to be referred to. The tubular sleeve 10 is provided upon its exterior, near and spaced from its inner end with a roughened or corrugated portion prefer- 65 ably formed by perforations 12, affording outwardly extending gripping teeth 13, more or less similar to the teeth of an ordinary grater. The inner layer 14 of broom corn or straw is disposed about the lower end of the sleeve 10, in engagement with the grip- 70 ping teeth 13, to be held thereby against separation from the sleeve 10. This inner layer of broom corn or straw is bound to the toothed surface of the sleeve 10 by means of a wire 15, attached thereto by having its 75 starting end passed through an apertured attaching tongue 16, which is preferably stamped from the material of the sleeve 10, as shown. This wire is wound in suitable layers about the inner layer of broom corn 80 or straw 14, as shown.

The numeral 17 designates supplemental attaching strips or plates which have their inner faces roughened or corrugated throughout their entire length, preferably 85 by means of perforations affording inwardly extending teeth 18, more or less similar to teeth of an ordinary grater. The upper ends of these toothed plates engage the upper toothed portion of the sleeve 10, (the 90 inner layer 14 of broom corn or straw terminating at a point below and spaced from the upper end of the toothed portion of the sleeve 10), while the lower portion of the same engages the exterior of the inner layer 95 14, serving to bind it to the sleeve 10. The teeth of the supplemental attaching plates or strips 17 are preferably irregularly arranged, whereby they will more easily inter-fit with the teeth of the sleeve 10. The 100 wire 15 is preferably wound a suitable number of times about the lower ends of the supplemental plates or strips 17, serving to securely bind them to the layer 15.

The numeral 19 designates the outer layer 105 of broom corn or straw, which surrounds the inner layer 14, in engagement with the upper ends of the supplemental attaching plates or strips 17 and the upper end of the toothed portion of the sleeve 10. This outer 110

layer 19 is securely bound to the sleeve 10 by winding the wire 15 thereabout also serving to bind the upper ends of the plates 17 to the sleeve 10. In heavy brooms, I have found that the supplemental strips 17 are very important, as they aid in holding the broom corn or straw upon the tubular sleeve, while in light brooms, satisfactory results are obtainable by dispensing with the supplemental strips. After the outer layer 19 of broom corn or straw is thus applied to the sleeve 10, a split lock-sleeve 20 is applied to the upper portion of the sleeve 10, and surrounding the shank 21 formed of the material of the outer layer 19. This lock-sleeve is held against longitudinal movement away from the brush or body portion of the broom, by downwardly bent tongues 22, preferably stamped from the upper end of the sleeve 10, as shown. The wire 15 passes through the slit of the lock-sleeve 20 and is wound a suitable number of times within an exterior annular groove 23 thereof, the finish end of the wire being attached or tied to a perforated tongue 24, formed upon a plate 25, preferably by slitting the plate diagonally and bending the material outwardly, as clearly shown in Fig. 7. The plate 25 is arranged within the lock-sleeve 20 while the tongue 24 thereof extends through the slit of the lock-sleeve, such tongue being bent down after the finish end of the wire is tied thereto, as shown.

The numeral 26 designates a broom handle, adapted to be removably mounted within the sleeve 10. This broom handle, is normally locked within the sleeve 10, by a split clamping ring 27, surrounding said sleeve 10 outwardly of and adjacent the tongues 22. The locking ring 27 is circumferentially contracted by an adjusting bolt 28, carrying a winged nut 29.

It is to be understood that the form of my invention herewith shown and described, is to be taken as a preferred example of the same, and that various changes in the shape, size and arrangement of parts may be resorted to without departing from the spirit of the invention or the scope of the subjoined claims.

Having described my invention, I claim:—

1. In cleaning apparatus, the combination with a sleeve having its outer surface roughened, a layer of brush material sur-

rounding the sleeve and engaging a portion 55 of the roughened surface thereof, a supplemental attaching plate having its inner surface roughened and engaging a portion of the roughened surface of the sleeve and the exterior portion of said layer, and means 60 to bind the layer and supplemental attaching plate to the sleeve.

2. In cleaning apparatus, the combination with a sleeve perforated to provide outwardly extending teeth, a layer of brush 65 material surrounding the sleeve and engaging the lower portion of the toothed surface of the sleeve, supplemental attaching plates perforated for providing inwardly extending teeth engaging the upper portion 70 of the toothed surface of the sleeve and the exterior of said layer, means binding the layer and supplemental attaching plates to the sleeve, and a handle having one end thereof inserted within the sleeve. 75

3. Cleaning apparatus comprising a tubular casing provided near its free end with tongues stamped therefrom, brush material surrounding the opposite end of the tubular casing and bound thereto, a lock-sleeve surrounding a portion of the tubular casing and brush material with the said tongues bent downwardly about the outer end thereof, and a contractile and expandable clamping ring engaging the tubular sleeve outwardly 85 of the adjacent said tongues. 80

4. Cleaning apparatus comprising a tubular casing adapted to receive a handle and provided upon its exterior surface with friction means, brush material surrounding 90 the tubular casing in engagement with the friction means with a portion of the friction means extending outwardly beyond the same, a supplemental plate having its inner face provided with friction means a portion of which engages the exposed friction means of the tubular casing and a portion of which engages the exterior surface of the brush material, means to bind the supplemental plate to the tubular sleeve, and 100 means to bind the supplemental plate to the exterior surface of the brush material. 95

In testimony whereof I affix my signature in the presence of two witnesses.

JAMES C. HIGHTOWER.
